UNITED STATES PATENT OFFICE.

JOHN FRANCIS SHEA, OF TAMPA, FLORIDA.

SIGNALING APPARATUS FOR SUBMARINE BOATS.

1,009,800.

Specification of Letters Patent. Patented Nov. 28, 1911.

Application filed February 20, 1911. Serial No. 609,808.

To all whom it may concern:

Be it known that I, JOHN FRANCIS SHEA, a citizen of the United States, residing at Tampa, in the county of Hillsboro and State 5 of Florida, have invented certain new and useful Improvements in Signaling Apparatus for Submarine Boats; and I do hereby declare the following to be a full, clear, and exact description of the invention, such as 10 will enable others skilled in the art to which it appertains to make and use the same.

The present invention relates to signaling apparatus for ships, more especially to vessels of the sub-marine type, and proposes a 15 construction whereby such vessels may be equipped with means for signaling when afloat or submerged; and wherein the apparatus is serviceable to assist in rescuing the vessel in the event of its becoming disabled when submerged.

The invention proposes the mounting of a mast on a buoyant support or raft which is carried by, and as a fixed part of, the sub-marine boat, said mast being equipped with 20 a yard arm designed to carry the transmitting and receiving wires of a wireless system; and also applicable to serve in place of the mast now used in connection with the visible code system for signaling when the ship is on 25 the surface. The connections between the raft and the vessel are such that when the boat is submerged the raft may, from within the boat, be readily released to allow the raft to float to the surface whereby to bring the 30 vessel into wireless communication with other points.

With these and other objects in view the invention consists in the arrangement and combination of parts hereinafter claimed, 40 and while the invention is not restricted to the exact details shown and described, still for the purpose of disclosure reference is had to the accompanying drawings, in which like reference characters designate the 45 same parts in the several views, and in which—

Figure 1 is a central vertical sectional view of the apparatus and a portion of the sub-marine vessel. Fig. 2 is a side elevation,

partly broken away, of the raft and mast. 50 Fig. 3 is a top plan view of the structure shown in Fig. 1. Fig. 4 is a top plan view of the deck of the vessel as equipped for carrying the raft. Fig. 5 discloses the gearing for releasing the raft from the vessel. 55 Fig. 6 is a detail sectional view of the releasable connection employed, and Fig. 7 is a top plan view, partly in section, of the part shown in Fig. 6.

Referring to the several views in further 60 detail and with like reference characters indicating corresponding parts in the different figures, 1 designates the upper deck or bulk-head of a sub-marine boat which carries, through the medium of a series of 65 cradles 2, a buoyant support or raft on which is mounted the signaling apparatus. This apparatus consists of a mast 1^a and a yard arm 1^b constructed of tubular aluminum or steel, and to said arm 1^b wires 1^c 70 and other parts are connected for wireless signaling. This equipment (1^a and 1^b) is also serviceable in connecting, with its usual signaling service of marine vessels, and it is further adapted for the installation of telephone and telegraph service. 75

The raft comprises a pair of air tight tanks 3 to which is secured a deck consisting of a middle plank 4, side planks 5, connecting cross planks 6, and a pair of 80 longitudinally extending beams 7 that are secured to the under sides of said cross planks (see Figs. 1 and 2). At either end the buoying tanks 3 are provided with metal bands or strips 8 connected with the deck 85 and having each an end terminating in a claw 9 through the medium of which the raft is detachably connected with the sub-marine vessel. There may be for each vessel more than one of these rafts and the accompanying equipment if necessary. 90

The means for connecting the raft with the vessel and for effecting the release of the former consists of four brackets 10 (2 being shown) having web portions 11 which 95 seat against and are secured to the under side of the deck 1 through the medium of bolts 12. The openings in the deck for these

connections are made water-tight by suitable packings 13. Journaled within the web 11 and an arm 14 on each of the brackets is a shaft 15 having its upper end provided with a half nut 16 adapted to pass through a similar shaped opening 17 in the claw 9, and when turned to engage said claws and secure the raft to the vessel. On their inner ends the shafts 15 are provided with beveled pinions 18 meshing with similar pinions 19 mounted on a pair of shafts 20, which shafts 20 are adapted to be turned for releasing the raft through the medium of a manually operated gearing comprising a shaft 22, cone gears 23—24 and a hand turning wheel 25. The signaling apparatus carried by the raft is adapted to have signal controlling connection with the vessel through the medium of a suitably insulated conductor cable 26 that extends through the mast 1^a, and has a joint or coupling 27 where it passes through the deck 1. A hawser 28 also connects the raft with the boat and is intended to be used for towing purposes. The cable 26 and hawser 28 are ordinarily stowed within a housing on the deck 1, which consists of a casing or chest 29 which has a removable cover 30, said cover being normally held closed through the medium of the deck beams 7 seating thereon, as shown in Fig. 1. The chest 29 is provided with a transverse partition 30' forming a chamber within which is swivelly mounted a sheave 31 provided with a hawser pulley 32 and adapted to have universal movement. The purpose of the sheave 31 is to assist in the reeving of the necessary cables, etc., for the purpose of raising the boat in the event of the same becoming disabled while submerged. The structure of the sheave 31 and its manner of operation are disclosed in my co-pending application Ser. No. 592,708, dated November 16, 1910, and no claim thereon is made in the present case. For stabilizing the signaling apparatus when the same has been released and floated the raft is provided with an equilibrator comprising two pairs of weighted arms 33 having pivotal connections 34 with the beams 7. The weighted ends of each pair of said arms are slightly spaced apart and connected by a bolt 35, and on one of said bolts there is pivotally mounted a link 36 adapted to be connected to the other bolt by having a hooked end 37 which engages therewith, when said arms are in functional position. In their normal position the arms of the equilibrator are supported within the deck of the raft through the medium of a chock or block 38 (see Fig. 1) which seats loosely upon the deck 1, and when in position serves as a partition for the coils of the cable 26 and hawser 28.

It is evident that the details of construction and the arrangement of parts may be

varied by those skilled in the art without departing from the spirit of my invention and, therefore, I do not wish to be limited to such features, except as may be required by the claims.

What I claim is:—

1. The combination with a sub-marine boat, of a signaling apparatus therefor including a mast, a raft supporting said mast carried by the boat, a conductor cable and a hawser connecting said apparatus with the boat, a casing in which said cable and hawser are adapted to be coiled, a removable closure for said casing adapted to be held in position by the raft when said raft is submerged and released when the raft is floated, and means for releasing said raft to float when the boat is submerged. 70

2. The combination with a sub-marine boat, of a signaling apparatus therefor including a mast, a raft supporting said mast, said raft comprising air-tight tanks, bands surrounding said tanks provided with claws, means engaging with said claws for holding the raft to the boat; a conductor cable and hawser connecting said raft with the boat, and means within the boat for effecting the release of said claws to permit the raft to float when the boat is submerged. 85

3. The combination with a sub-marine boat, of a signaling apparatus therefor including a mast, a raft supporting said mast and comprising buoyant supports, cradles on said boat supporting said buoyant supports, a conductor cable and a hawser connecting said apparatus with the boat, a casing mounted on the boat intermediate said cradles and adapted to have coiled therein said cable and hawser; a removable closure for said casing adapted to be held in position by the raft when said raft is submerged and released when the raft is floated; and means for releasing said raft to float when the boat is submerged. 95 100

4. The combination with a sub-marine boat, of a signaling apparatus therefor including a mast, a raft supporting said mast, means for releasably securing said raft to the boat, an equilibrator for said raft; a conductor cable and a hawser connecting said apparatus with the boat, a casing in which said cable and hawser are adapted to be coiled, a block mounted within said casing and adapted to support the equilibrator in inoperative position; a removable closure for said casing adapted to be held in position by the raft when said raft is submerged and released when the raft is floated; and means for releasing said raft to float when the boat is submerged. 115 120

5. The combination with a wireless signaling apparatus including a mast and a raft for floating the same on water, of an equilibrator for said raft comprising a pair of pivotally mounted ballast irons. 130

6. The combination with a wireless signalling apparatus including a mast, and a raft for floating the same on water, of an equilibrator for said raft comprising a pair of
5 pivotally mounted ballast irons, and a link connecting and holding said irons against relative movement.

In testimony whereof, I affix my signature, in presence of two witnesses.

JOHN FRANCIS SHEA.
